(57) **CLAIM**

The ornamental design for a camera filter, as shown and described.

DESCRIPTION

FIG. 1 is a front, right and top perspective view of a camera filter showing our new design;

FIG. 2 is a front elevational view thereof;

FIG. 3 is a rear elevational view thereof;

FIG. 4 is a left view thereof;

FIG. 5 is a right view thereof;

FIG. 6 is a top plan view thereof;

FIG. 7 is a bottom plan view thereof;

FIG. 8 is a rear, right and top perspective view thereof;

FIG. 9 is an exploded perspective view thereof;

FIG. 10 is an enlarged portion view taken from encircled portion labeled, “FIG. 10” in FIG. 4;

FIG. 11 is an enlarged portion view taken from encircled portion labeled, “FIG. 11” in FIG. 6;

FIG. 12 is an enlarged portion view taken from encircled portion labeled, “FIG. 12” in FIG. 7; and,

FIG. 13 is an enlarged portion view taken from encircled portion labeled, “FIG. 13” in FIG. 9.

The dashed-dot lines form the boundary of the enlarged portion view of FIGS. 10, 11, 12, and 13 in FIGS. 4, 6, 7, 9, 10, 11, 12, and 13 form no part of the claimed design.

1 Claim, 13 Drawing Sheets
